CONSTRUCTION OF EXPANSION JOINTS

Ernest Meyer and Gavotte J. Irwin, Akron, Ohio,
assignors to The B. F. Goodrich Company, New
York, N. Y., a corporation of New York

Application August 10, 1939, Serial No. 289,406

6 Claims. (Cl. 94—18)

This invention relates to the construction of expansion joints in slab floor or pavement constructions, and is particularly useful in connection with the laying of floors and pavements of concrete or other plastic composition.

In the construction of concrete floors and pavements it is necessary to form the floor or pavement of separate slabs with spaces provided therebetween to compensate for expansion and contraction of the floor or pavement due to changes of temperature. The spaces may be filled with a water-sealing plastic material such as bituminous compositions, or compressible sealing strips of rubber-like material may be employed to close the spaces so that water and dirt is prevented from entering and accumulating in the expansion spaces. For this purpose a resilient rubber expansion joint strip such as that of the Dewhirst and Meyer Patent No. 2,156,681 dated May 2, 1939 may be used.

As it is necessary to keep the surface of floors and pavements smooth and free from projections or shoulders, it is usually desired to employ dowel pins embedded in the adjacent slabs and extending therebetween across the joint to transfer the paving loads from slab to slab and prevent relative vertical movement of the slabs due to shifting of road ballast or action of frost or surface water.

The problem of providing a removable form to mold the expansion joint space is made more difficult by the presence of the dowel rods and makes advisable the use of a form which will support the rods in proper position until the slabs are completed and will permit removal of the form from both.

The principal objects of this invention are to provide for conveniently molding the walls of the space while supporting the dowel rods in proper position, to provide ease of placement and removability, to provide for forming a rebate to seat a resilient sealing strip between slabs, and to provide conveniently for simultaneous embedding of a lower sealing strip in the joint.

These and other objects will appear from the following description and the accompanying drawing.

Of the drawing

Fig. 1 is a perspective view of the form ready for pouring of the concrete, parts being broken away and parts shown in section.

Fig. 2 is a cross sectional view of a pavement showing portions of adjacent concrete slabs, the dowel pin, and the form and lower sealing strip in place.

Fig. 3 is a perspective view of the resilient dowel support.

Fig. 4 is a perspective view of a modified form of the invention, parts being broken away and parts shown in section to illustrate its construction.

Fig. 5 is a perspective view of the bottom sealing strip.

Referring to the drawing, the numerals 10, 11 designate adjacent spaced slabs of concrete having an expansion space 12 therebetween. To provide for supporting a resilient expansion joint filler at the surface of the slabs, the shoulders of the slabs adjacent the space may be rebated as at 13, 14. A channel shaped resilient strip 15 is provided to seal the space at the bottom so that water cannot enter the joint from below and has wings 16, 17 embedded in the concrete. The strip 15 preferably is formed with its inner walls 15a, 15b upwardly converging as shown in Fig. 5 so that it may be mounted upon the form temporarily simply by gripping the same between such walls without the provision of special attaching devices, and may be readily detached from the form to leave the strip in the bottom of the expansion void.

Load-transferring dowel rods 18 are embedded in the slabs across the joint. These rods may be of solid metal with clearance spaces provided 30 at their ends in any desired manner as by use of tubing forms placed over the ends of the rods, or the rods may be of composite telescoping type. In either case the rods may be lubricated before being embedded in the concrete so as to facilitate sliding movement of the rod with respect to the slabs.

To provide for forming the space 12 a pair of similar strips or plates 19, 20 of strip material such as sheet metal are mounted together in 40 spaced relation by spacing strips 21, 22 to which the strips 19, 20 are secured by screws 23 or other suitable fastening means.

For clearing the dowel rods so that the form may be removed after adjacent slabs have been 45 formed, V-shaped notches or slots 25 are formed in the lower margins of strips 19, 20 at the proper intervals. The notches have arcuate throats having the same radius as the rods 18.

Strips 27, 28 of sheet material having the desired thickness may be affixed to the exposed 50 faces of strips 19, 20 at their upper margins for forming the rebates 13, 14. If desired, the strip 22 may be omitted as in Fig. 4 and where the strips 19, 20 are of springy metal removal of the 55 form from the poured joint is facilitated by the

spring of the plates and the absence of the strip 22.

The channel strip 15 of resilient material may conveniently be placed by straddling it about the bottom of the form so that its flanges 16, 17 extend outwardly above the bottom of the form. The resilience of the strip causes the walls 15a, 15b thereof to grip the form, holding the strip temporarily in place. When the concrete is poured thereabout the flanges are embedded therein and the channel strip remains in the concrete when the form is withdrawn.

The rods 18 may conveniently be employed for assisting in supporting the form in place. For this purpose a supporting structure of wire 30 may be provided to support the ends of the dowel rods and to support the form midway of their length. A convenient supporting structure may be provided by welding U-shaped wire members 31 to straight lengths 32, 33 of similar wire, the wires 32, 33 being arranged at such a height on the limbs of the U-shaped members 31 as to provide supports for the rods while at the same time properly spacing the U-shaped members. Smaller U-shaped wire members 34 may be welded to the members 31 at their centers to support the channel strip 15 of the form.

To provide for closing the slots 25 to prevent entrance of concrete at the slots and at the same time to assist in supporting the rods 18, and to provide for ready removal of the supporting means, independently removable blocks 35 of resilient yieldable material such as soft vulcanized rubber or sponge rubber or other resilient rubber-like compositions are provided. These blocks are as thick as the form and are of the shape generally of a truncated isosceles triangle as viewed from the side, and adapted resiliently to fill the slots 25. The tops of the blocks are concavely formed as at 36 to provide a rest for the dowel bars. To provide for holding the blocks in place while permitting the faces of the blocks to lie flush with the outer faces of the form, lugs 37, 38 of less width than the blocks by the combined thickness of the strips 19, 20 are provided centrally of the inclined sides of the blocks. These lugs act also as spacers to space the strips 19, 20 apart. After the concrete is formed the blocks may be removed one at a time from the joint after the form has been lifted, the resilient pliable properties of the blocks permitting them to be distorted to remove them from below the dowel rods. The downward pressure of the dowel bars compress the blocks somewhat so that when forced out from beneath the bars, the blocks spring upward and greatly facilitate the removal.

A modified form of independently removable resilient filler block is shown in Fig. 4. In this form of the invention, the block 50 is of truncated isosceles form but higher than the tops of the dowel rods and wider than the slots 25 and of the same thickness as the space between the strips 19, 20. A horizontal aperture 51 of the shape and size of a dowel rod is formed therethrough at such a height as to support the dowel in the desired position. The block 50 is split vertically from the aperture to its base as at 52 to permit removal of the block by spreading of the split portion.

In either embodiment of the invention, the resilience of the blocks seals the slots in the form against entrance of concrete and permits removal of the blocks after the dowel rods are in place and embedded in the concrete. The blocks are

not readily subject to wear and may be used over and over again.

These and other modifications may be made without departing from the spirit of the invention as it is defined by the following claims.

We claim:

1. A form assembly for making an expansion joint, said assembly comprising a form structure having notches in the lower margin thereof for accommodating load transfer devices, removable spaced-apart blocks of resilient rubber-like material disposed in said notches between the walls of the form beneath said devices to support the latter and close the notches, said blocks being removable independently of one another from the form, and a joint bottom strip of resilient rubber-like material in channel form receiving the bottom margin of the form and said blocks and comprising walls in converging relation adapted to grip the form and the bottom portions of said blocks resiliently between them.

2. A form for an expansion joint between floor or paving slabs, said form comprising a pair of spaced form strips notched at a margin thereof to clear a dowel rod, and a block of resilient rubber-like material adapted to be removably positioned substantially to fill the space between the strips at the notched portion, said block having integral retaining lugs for locating it with respect to the notched portion and for holding it temporarily in place, and said block having a seat for said dowel-rod.

3. A form for making an expansion joint, said form comprising a structure notched at its lower margin to accommodate a load-transfer device, and a block of resilient rubber-like material having a seat for said device and being removably positionable in said structure at the notch in relation to support said device on said seat upon removal of the notched structure from the joint, said block being of sufficient length to close the notch opening in the structure, but of a length not substantially greater than its height so as to permit dislodging the block from beneath the load-transfer device by tilting and compressing the block in the joint.

4. A form for making an expansion joint, said form comprising a pair of spaced-apart plates notched at the lower margin thereof to accommodate a load-transfer device, and a block of resilient rubber-like material having a seat for said device and being positionable removably at the notch between the plates in relation to support said device on said seat in the joint upon removal of the plates from the joint, said block being of a size and shape substantially closing the notch opening in the plates and having retaining portions integral therewith and projecting between said plates only a limited extent beyond the notch in such relation as to permit dislodging the block from beneath the load-transfer device by tilting and compressing the block in the joint after removal of said plates.

5. A form for making an expansion joint, said form comprising a pair of spaced-apart plates having notches at spaced-apart positions along the lower margin thereof to accommodate spaced-apart load-transfer devices, and blocks of resilient rubber-like material having a seat for said device and being positionable removably at the notches between the plates in relation to support said load-transfer devices on said seats in the joint upon removal of the plates from the joint, said blocks being of a size and shape substantially closing the notch openings in the plates and

having retaining portions integral therewith and projecting between said plates only a limited extent toward one another in such relation as to permit dislodging each block individually from beneath its load-transfer device by tilting and compressing the block in the joint.

6. Means for supporting a load-transfer device and closing the notch opening of an expansion joint form, said means comprising a block of resilient rubber-like material positionable removably at the notch of the form in relation to support the load-transfer device in the joint upon

removal of the notched structure from the joint, said block having a seat for said device and being of a size and shape to close substantially the notch opening in the structure and having ears integral therewith and projecting therefrom in off-set relation to the face of the block for reception within said structure beyond the notch to locate and retain the block temporarily in the form.

ERNEST MEYER.
